(57) **CLAIM**

The ornamental design for a self-cooled beverage container, as shown and described.

DESCRIPTION

FIG. 1 is a top perspective view of the ornamental self-cooled beverage container according to the invention;

FIG. 2 is a side view of the self-cooled beverage container of FIG. 1;

FIG. 3 is a top plan view of the self-cooled beverage container of FIG. 1; and,

FIG. 4 is a bottom plan view of the self-cooled beverage container of FIG. 1.

1 Claim, 2 Drawing Sheets

FIG. 1

FIG. 2

FIG. 3

FIG. 4
